UNITED STATES PATENT OFFICE.

JULIUS RITTER, JR., OF RACINE, WISCONSIN, ASSIGNOR TO HARTMANN TRUNK COMPANY, OF RACINE, WISCONSIN, A CORPORATION OF WISCONSIN.

GARMENT-HANGER TRACK.

Application filed January 25, 1926. Serial No. 83,575.

This invention relates to improvements in garment hanger tracks.

Wardrobe trunks of the modern type are provided with garment hanger tracks for supporting garment hangers thereon. The tracks are usually provided with extensions to permit the hangers mounted thereon to be moved outwardly on the extensions and separated for convenience in removing or replacing garments thereon. The wardrobe section of the trunk is usually open at its upper end and is provided with a top cover which is hinged to one of the sections.

It is one of the objects of the present invention to provide an improved extensible track of the above mentioned type in which the track proper is formed of sheet metal shaped to form a rigid structure which is of very light weight, and presents a finished appearance.

A further object of the invention is to provide a garment hanger track having end extensions hinged to the fixed portions to form a rigid structure in both positions of use and to also form a smooth upper surface for the garment hangers to slide thereover.

A further object of the invention is to provide a garment hanger track which is of simple construction, is strong and durable and is well adapted for the purpose described.

With the above and other objects in view, the invention consists of the improved garment hanger track and its parts and combinations as set forth in the claims and all equivalents thereof.

In the accompanying drawing in which the same reference characters indicate the same parts in all of the views:

Fig. 1 is a transverse sectional view of the upper portion of the wardrobe section of a wardrobe trunk provided with the improved garment hanger track;

Fig. 2 is a vertical sectional view of the trunk section, the garment hanger being shown in folded position;

Fig. 3 is a side view of the hanger, the trunk part being in section;

Fig. 4 is a transverse sectional detail view on a larger scale taken on line 4-4 of Fig. 3;

Fig. 5 is a detail view of the hinge connection; and

Fig. 6 is a sectional detail view of one of the fixed tracks showing its connection with a U-shaped arm.

Referring to the drawing the numeral 8

indicates the wardrobe section of a wardrobe trunk which is formed with an open front and top closed by the other trunk section and a top cover not shown. The improved garment hanger track is formed and secured to the upper open end portion of the section in a manner which will now be described. A metal collar or frame of U-shape in plan view is mounted in the upper portion of the wardrobe section and is provided at opposite sides with depending U-shaped arms 10 having upturned inner end portions 11. Fixed tracks 12 formed of strips of sheet metal folded lengthwise to provide tubes of oblong shape in cross section have outwardly angled end portions 13 which are connected by rivets 14 to depending plates 15 forming part of the frame. The upper inner end portions 11 of the arms 10 extend through openings 12' into the fixed tracks and are connected thereto by rivets 16. Filler plate members 17 are placed alongside of the brackets and secured by the rivets 16 to fill said spaces 12'. The outer end portions of the fixed tracks are open and formed with squared ends to receive the hinge leaf members 17' inserted therein. Said hinge leaf members are formed of thick metal and have eyed ends 18 which overlap with the eyed ends 19 of companion hinge leaf members 20 mounted in the open ends 21 of extensible tracks 22, and pintle pins 23 extend through the eyes to connect the two parts together. Rivets 24 extending through the respective track members and the hinge sections securely connect the parts together. To form a smooth upper surface for garment hangers to slide on, the inner end portions 22' of the extension tracks extend over the hinge pins 23 in a plane flush with the upper portion of the fixed tracks and have inner curved end edges 25 to permit folding of the extensions as shown in Fig. 1, while the outer side inner end edges 26 are squared to abut each other when the extension sections are aligned with the fixed tracks as shown in Fig. 1. The squared and rounded edges also limit the inward and outward movement of the extensible tracks. The lower side inner end portions of the fixed extension tracks are arranged in the same manner as the upper portion.

As thus hinged together the two track sections present flush upper and opposite side surfaces without the formation of shoulders so that garment hangers resting on the tracks

can easily slide from one track section to the other.

The lower outer end portions of the extension tracks 22 are open to receive extension members 27 and 28 rigidly secured thereto. The member 27 is provided with an eye and the member 28 is in the form of a hook which lockingly enters the eye to hold the two parts together.

10. From the foregoing description it will be seen that the garment hanger track is of very simple construction, is strong and durable and light in weight, and is well adapted for the purpose described.

15. What I claim as my invention is:

A garment hanger track comprising a tubular fixed track member having an open front end and outwardly angled inner end portions, said members also having a lower 20 opening, a plate to which the angled inner

end portions are rigidly connected, a U-shaped bracket having one end portion extending into the lower opening and rigidly connected to the track member, an eyed hinge member extending into the outer end of and connected to the fixed track member, a tubular horizontally movable track member having an inner open end, and an eyed hinge member extending into the open end of the movable track member and connected thereto, the eyed portions of both hinge members overlapping each other and being pivotally connected together, portions of the extensible track member extending over and under the hinge members and on the outer sides 30 thereof to form a flush upper and outer side surface between the two track members.

In testimony whereof, I affix my signature.

JULIUS RITTER, JR.
